UNITED STATES PATENT OFFICE.

CHARLES E. TEED, OF GRIFFIN'S CORNERS, NEW YORK.

AUTOMATIC WAGON-BRAKE.

SPECIFICATION forming part of Letters Patent No. 363,435, dated May 24, 1887.

Application filed January 13, 1887. Serial No. 224,247. (No model.)

To all whom it may concern:

Be it known that I, CHARLES E. TEED, a citizen of the United States residing at Griffin's Corners, in the county of Delaware and State 5 of New York, have invented certain new and useful Improvements in Automatic Wagon-Brakes; and I do hereby declare the following to be a full, clear, and exact description of the invention, such as will enable others 10 skilled in the art to which it appertains to make and use the same.

This invention relates to that class of wagon-brakes in which the brake-shoes are automatically applied to and released from the wheels 15 by the holding back and pulling of the team, such action of the team serving to operate the brakes through the medium of a longitudinally-movable draft-tongue.

The objects of the invention are to simplify 20 and strengthen the connections between the draft-tongue and the brake-bar, and to so arrange such connections as to permit a free pivotal movement of the tongue; and furthermore, to insure the quick application and release of 25 the brake-shoes, and also a powerful grip or holding action of the shoes upon the wheels.

To the above purposes the invention consists, first, in the combination, with a tongue-carrying frame pivoted between the wagon-hounds and a draft-tongue arranged to slide 30 longitudinally upon the pivot-bolt of the frame, of a pair of levers pivoted upon the hounds directly above the pivot-bolt and connected with the tongue and with a brake-bar, 35 so as to operate the latter by the movements of the tongue, as hereinafter described and claimed.

The invention further consists in the combination, with the brake-beam, of a pair of 40 triangular or wedge-shaped brake-shoes arranged to slide vertically at the ends of the beam or bar and normally sustained in their lowermost position by spring action, as hereinafter described and claimed.

45 The invention consists, finally, in certain peculiar and novel features of general construction and arrangement, as hereinafter described, and specifically pointed out in the claims.

50 In order that the invention may be fully understood I will proceed to describe it with

reference to the accompanying drawings, in which—

Figure 1 is a plan view of the front axle of a lumber-wagon with my improvements applied. Fig. 2 is an inverted plan view of the same. Fig. 3 is a central longitudinal section of the same on the lines 3 3 of Figs. 1 and 2. Fig. 4 is a detached view of one end of the 55 brake-bar and one of the brake-shoes.

In the said drawings, A designates the front axle of a lumber-wagon, or of any other similar vehicle; and B B designate the wheels thereof. Upon the upper side of the axle A are secured two bars, C C, which converge toward their front ends, and the rear ends of which are shown as connected by a curved bar, C'. The bars C C are the hounds of the wagon, and are connected together about midway of 60 their length, directly above their axle, by a cross-bar, C², as shown.

Between the ends c c of the hounds C, extending in front of the axle, is placed the tongue-carrying frame, which consists of two peculiarly curved bars, D D, connected together at their rear ends by metal bars d d above and below the bars D, and at their front ends by similar metal plates or bars, d' d' and d'' d''. In order to strengthen this frame and to increase its durability the edges or sides 75 of the bars D are bound with metal strips d³, as shown. As previously stated this frame is placed between the front ends of the hounds, and said frame is held in position by a bolt, E, which passes laterally through the front 80 ends of the hounds and also through the bars D. 85

F designates the draft-tongue, which extends between the front extremities of the bars D, at which point it is confined by the bars d' d'', and thence between the plates or bars d, where 90 it is confined between blocks d⁴ d⁴, which are in turn held between said plates d. The parts of the tongue, which lie thus within the tongue-carrying frame, are protected by metal plates e e' e'', and the plates e and the corresponding 95 portion of the tongue are formed with elongated slots e³, through which the pivot-bolt E passes, so as to permit an endwise movement of the tongue. The plate e', which covers the upper side of the tongue F, carries a U-shaped 100 loop, e⁴, beneath which lie the inner ends of two levers, G G, a pin, e⁵, extending downward

through said loop and into the tongue, and also passing through elongated slots or eyes *g* in the levers *G*. The said levers *G* are pivoted by pins *h* within loops *H*, similar to the loop *e*, which are secured upon the upper sides of the ends *c* of the hounds and directly over the pivot-bolt *E*, as shown. It will be observed that the relative position of the pivotal points of the tongue-carrying frame and of the levers *G*, as well as the pin *e*, are such as to prevent any impediment to the pivotal movement of the tongue by the levers relative to the hounds, so that the levers can be freely operated under all circumstances by the tongue.

15 The outer ends of the levers *G* are extended beyond the outer sides of the hounds, and to these ends are connected the front ends of rods *I*, which extend rearwardly between the axle and the cross-bar *C* to the brake-bar *J*. 20 The rear ends of the rods *I* are screw-threaded, and pass through the ends of the brake-bar, the said end of the bars being held adjustably between two binding-nuts, *i*, on each rod for the purpose of varying the throw of the bar 25 and to compensate for wear of the shoes.

The brake-shoes *K* consist each of a triangular or wedge shaped block, *k*, the three sides of which are inclosed by a metal plate, *k'*. The front part of each plate *k'* constitutes 30 the face of the shoe, while the rear part is sprung away from the block, as shown at *x*, so as to enter a recess, *j*, in the front side of the brake-bar near its end. A metal plate, *j'*, is secured to the front side of the brake-bar *J* at 35 each end thereof, so as to overlie the recess *j*, and each of these plates extends between the rear sides of the corresponding block, *k*, and the portion *x* of the plate *k'*, so as to support the brake-shoe upon the beam. These shoes 40 are placed upon the brake-bar with their bases downward, as shown, and the base of each shoe is formed with a notch or recess, *k*², within which enters the end of a spring-rod, *L*, which is secured to the under side of the brake-beam 45 *J* by staples *l*, the tendency of the spring-rod being to hold the brake-shoes in their lower-most position. By virtue of this arrangement

of the brake-shoes, whenever the team holds back so as to force the tongue backward, the consequent forward movement of the brake-bar will bring the brake-shoes against the wheels, and the latter will, by their revolution, move the shoes upward, and cause them to be firmly wedged between the tires of the wheels and the brake-bars, thus giving a firm 55 grip to the shoes.

A pair of metal strips, *m*, extend along the upper sides of the bars *C*, and a similar pair of strips, *m'*, extend along the under sides of said bars, said strips overlying the cross-bars *C*, and underlying the axle *A*, so as to securely unite the parts. At their rear ends the strips *m'* are bent to form loops *m*², in which the brake-beams *J* are supported and work.

Having thus described my invention, what I claim as new therein, and desire to secure by Letters Patent, is—

1. The combination, with the pivoted tongue-frame, the sliding tongue confined therein, and the brake-levers pivoted upon the frame and connected pivotally to the said tongue, of the brake-bar *J*, having the recesses *j* and their covering-plates *j'*, and carrying the spring-rod *L* of the triangular brake-shoes *K*, having the plates *k'* sprung away, as at *x*, 75 and the recesses *k*² at their lower ends to receive the ends of the rod *L*, substantially as specified.

2. The combination, with the wagon-hounds *C* and the tongue-carrying frame composed of the bars *D* and cross-bars *d* *d'* *d*², of the pivot-bolt *E*, extending through said frame and hounds, the longitudinally moving tongue having the loop *e* and pin *e*², the levers *G*, having elongated slots *g* *g* and pivoted in loops *H* and in the said loop *e*, the rods *I*, and the bar *J*, connected to said rods by the nuts *i*, substantially as set forth.

In testimony whereof I affix my signature in presence of two witnesses.

CHARLES E. TEED.

Witnesses:

DANIEL SMITH,
AUGUSTUS H. TODD.
